**LOADING PLATFORM FOR GARBAGE
DISPOSAL MACHINE**

Harry Higer, Detroit, Mich.

Application November 15, 1955, Serial No. 546,946

5 Claims. (Cl. 241—301)

This invention relates to matter cutting or disintegrating apparatus and particularly to such apparatus provided with an improved loading platform. The present application is a continuation-in-part of my co-pending applications Serial No. 352,882, filed May 4, 1953, now abandoned, for Disposal Apparatus; and Serial No. 420,286, filed on April 1, 1954, for Disposal Apparatus.

In the use of machines disclosed in my said co-pending applications, provision of matter-loading hopper or similar means proved to be a difficult problem. It has been found that conventional hoppers used in machines of this general nature are wholly unsatisfactory from the standpoint of safety, convenience and efficiency of the operation of the apparatus. Particularly, it was found that hoppers provided directly above the machine are highly undesirable, since pieces of matter including hard objects such as pieces of metal or glass fly out from the machine upwardly or sidewise, presenting danger to personnel. Pieces of matter and water thrown and splashed around the machine make it necessary to keep the hopper covered when the machine is operating. However, with the hopper being even partly covered, loading of the machine is inconvenient, and taking the cover off in spite of the above difficulties is nevertheless necessary for proper loading of the matter into the machine. In addition, the cutting blades are partly exposed and can be easily reached by hand, providing temptation to reach into the recess to push stuck pieces downwardly or for cleaning the machine. Such an operation presents considerable danger. Moreover, it was also found that it is necessary to load the matter into the machine in small portions, in order to prevent overloading of the hopper or causing the matter to support itself therein while the rotor is running idle. This, in turn, requires throwing the matter into the hopper piece by piece or in small portions, either by hand or by shoveling it from some container or a pile on the floor. Such conditions are highly undesirable as unsanitary, inefficient and tiring.

One of the objects of the present invention is to provide an improved apparatus of the character described herein, whereby the difficulties and disadvantages explained above are overcome and largely eliminated.

Another object of the present invention is to provide a matter-cutting or disintegrating machine having an improved loading platform which can support considerable amount of matter thereon, which matter can be pushed into the machine in small portions without the necessity of raising it or carrying it to the hopper in small portions from another container or raising it from the floor.

A further object of the present invention is to provide a matter-cutting or disintegrating machine having an improved loading platform which prevents hard pieces of material such as pieces of glass or metal from flying out of the machine, as well as the soft matter and water from being thrown around and splashed around the machine.

A still further object of the present invention is to provide a matter-cutting or disintegrating machine having an

2

improved loading platform which covers the matter receiving recess of the machine and makes it impossible for the personnel to reach into the recess with one's hand.

A still further object of the present invention is to provide a machine for cutting or disintegrating matter having an improved loading platform and means whereby the matter is transferred from said platform into the matter receiving recess of the machine and discharged therein in the direction of the rotor rotation.

10 A still further object of the present invention is to provide a machine for cutting or disintegrating matter, having an improved loading platform provided with means to separate and to arrest larger pieces of ferrous metals.

Further objects and advantages of this invention will be apparent from the following description and appended claims, reference being had to the accompanying drawings forming a part of this specification, wherein like reference characters designate corresponding parts in the several views.

20 Fig. 1 is a perspective view illustrating a garbage disposal machine provided with a loading platform embodying the present invention.

Fig. 2 is a top view of the machine of Fig. 1.

25 Fig. 3 is a fragmentary sectional view taken in the direction of the arrows on the vertical section plane passing through the line 3—3 of Fig. 2.

Fig. 4 is a fragmentary sectional view taken in the direction of the arrows on the section plane passing through the line 4—4 of Fig. 2.

30 It is to be understood that the invention is not limited in its application to the details of construction and arrangement of parts illustrated in the accompanying drawings, since the invention is capable of other embodiments and of being practiced or carried out in various ways. Also it is to be understood that the phraseology and terminology employed herein is for the purpose of description and not of limitation.

35 In accordance with the invention, I discard the use of conventional hoppers in connection with machines of this nature. I provide a substantially horizontal platform which has the double function of covering the top of the machine to prevent pieces of material from flying out therefrom, and also to support a considerable amount of matter to be cut and to permit spreading such matter thereon in a relatively thin layer, and thus to enable the operator to separate and take out objects such as bottles, pieces of metal and the like. Such a platform is arranged preferably centrally of the machine but overhanging the same for some distance, such as 1-3 feet, depending on the size of the machine and other conditions. The matter is passed from the platform to the recess through a chute which is inclined and, therefore, passes the matter into the machine by gravity, permitting the matter to slide into the machine. I prefer to discharge the matter into the machine at one side of the center line of the rotor and in the direction of the rotor rotation, whereby the matter is drawn into the recess by the action of the cutting blades rather than pushed out therefrom. The inclined chute is made sufficiently long to prevent the operator from trying to reach into the recess with his hand, whereby possibility of accidents from such a cause is eliminated.

40 Retaining walls may be provided at least around the three sides of the table in order to prevent the matter from falling off the table, and yet to permit loading of the machine from one of its sides. A magnet may be provided adjacent the matter-receiving opening in the table to arrest pieces of ferrous metals. It is also desirable to provide a ridge at such opening adapted to serve as a stop for such pieces of metal as the same are pushed along the table toward the opening. Means are also provided to discharge water at the upper end of the chute in order to facilitate sliding of the matter into the machine, and for washing the machine.

An apron may be provided within the chute, which apron being hinged at its upper edge tends to keep itself closed to provide additional safety shield and yet be opened by the matter for passage thereof into the machine. With such a construction, when the chute becomes empty, and the matter does not serve to stop hard pieces from flying into the chute, the apron falls down and provides such means.

Referring to the drawings, there is shown therein by way of example a structure embodying the present invention. Referring specifically to the drawings, there is shown therein a matter-cutting or disintegrating machine comprising casing 10 and having a rotor 11 operatively mounted therein for rotation, said casing and said rotor being recessed to form an annular converging recess 12. A number of stationary cutting blades 13 are provided on the casing 10 while a number of moving blades 14 is provided on the rotor. Blades 13 and 14 meet in cutting engagement substantially along the bisector line of the cross section of the converging recess. Because the number of the blades on the casing is different from that on the rotor, only one pair of blades is in cutting engagement at the same moment of time in order that the entire power of the machine is applied to shearing the matter between only one pair of the blades.

The machine illustrated in the drawings in a general way is disclosed in detail in my said co-pending applications and no further description thereof for the purposes of understanding the present invention is deemed necessary herein.

In accordance with the invention there is provided above the matter-receiving recess 12 a loading table or platform comprising a horizontally extending shield 20 supported on the casing 10 with the aid of sub-structure 21 of any suitable character, capable of supporting the shield 20 and the weight of the matter that may be imposed thereon, as well as closing the space between the shield 20 and the casing 10. The shield 20 is preferably provided with upstanding flanges such as 22, 23 and 24. It is preferable to have such flanges at least along two meeting sides of the table 20 to form an angle as indicated at 25. It will be understood, however, that such angle need not have a sharp vertex but may be well loaded or have other configuration. The flanges are intended to prevent the matter from falling off from the platform while being pushed thereon. The size of the platform or shield 20 is made sufficiently large to cover the top of the machine and to overhang the same by a desired distance, as is best shown in Fig. 2.

At one of the corners of the platform there is provided a matter-receiving opening 30 which may be of any suitable size and shape. Leading from the opening 30 is an inclined chute 31 formed between the shield 20 and the inclined wall 32. The chute 31 leads into the matter-receiving recess 12 of the machine and comes thereinto on a tangent in the direction of rotation of the rotor, as is best shown in Fig. 2. By virtue of such an arrangement the matter falling into the recess is thrown forwardly by the blades of the machine, instead of being thrown back into the chute. An apron 33 is provided in the chute 31 by being hinged at its top, as indicated at 34, and is adapted to be opened by the matter sliding along the wall 32 but falling down and closing the chute 31 by its own weight. By virtue of such a construction, the receiving end of the chute 31 is closed substantially at all times for the splashing water and matter that may fly from the machine. Such closing is effected by the apron 33 or by the matter under the lower edge thereof. The chute 31 is made sufficiently long in order that an operator could not reach the blades with his arm through the opening 30. Such a construction satisfies an important safety requirement. A water discharge outlet 31a is provided at the upper end of the chute 31 as shown in Fig. 1 in order to facilitate sliding of the matter into the machine, and for washing the machine.

The machine embodying the present invention, par-

ticularly when made of a medium size for use in commercial institutions such as restaurants, hotels, hospitals and the like, can crush objects such as bottles, metal spoons and knives. However, the purpose of the machine is not to crush glass or metal and, therefore, means are provided to separate such matter and remove it from the platform before it falls into the machine. In the present embodiment of the invention such means are exemplified by permanent magnets or electro-magnets designated generally by the numeral 35 and disposed underneath the shield 20 near the opening 30. Should a metal article, such as a knife or a bolt, find its way to the loading platform, it will be drawn by the magnet either into direct contact with the platform or table 20 or into such close proximity as to offer sufficient resistance to its moving along the platform and thus to give an indication to the operator of its presence, or to contact ridge or stops 36 provided along the edges of the opening 30 to stop such metal articles. Thus the operator can easily notice presence of such articles on the platform, and he can remove them by hand and toss them into a container that may be provided for such purpose.

It should be understood that the platform 20 may be extended to the point when it would be not only the matter-receiving platform but would provide a working space, such as is required in a meat-cutting table and the like, and thus form a working table from which the cut-offs that would otherwise be thrown into the garbage for later disposal are immediately shoved off into the opening 30 for immediate cutting and disposal. With such a construction the flanges may be rearranged to suit the condition of the work at the table.

There is thus provided an improved loading table or platform for use in combination with my cutting and disintegrating machine, whereby the objects of the present invention and numerous additional advantages are attained.

I claim:

1. In an apparatus of the character described, a structure provided with a vertically extending matter-receiving recess having a rotor operatively arranged therein, a loading platform comprising a horizontally extending table arranged above said recess and having an opening for passage of the matter therethrough, upstanding walls provided along the edges of said platform, an inclined chute leading from the opening in said platform into said recess, and an apron provided in said chute and hinged at its top.

2. In an apparatus of the character described, a structure provided with vertically extending matter-receiving recess having a rotor operatively arranged therein for cutting the matter received in said recess, a matter-loading platform comprising a substantially horizontal rectangular table having matter-retaining walls along at least three of its sides and supported on the machine structure above said recess and overhanging the same, said table being provided at one of its corners with a matter-receiving opening, an inclined chute leading from said opening into said recess substantially diagonal of said table for passing the matter from said table into said recess at one side of the axis thereof and in the direction of rotation of said rotor.

3. In an apparatus of the character described, a structure provided with a vertically extending matter-receiving recess having a rotor operatively arranged therein for cutting the matter received in said recess, a matter-loading platform comprising a substantially horizontal table supported on the machine structure above said recess and having upstanding walls along its edges, said table being provided with a matter-receiving opening disposed laterally with respect to said recess, an inclined chute leading from said opening into said recess for passing the matter from said table into said recess, said chute having its discharge opening on one side of the rotor and discharging the matter in the direction of rotation of the rotor.

4. In an apparatus of the character described, a structure provided with a vertically extending matter-receiving recess having a rotor operatively arranged therein for cutting the matter received in said recess, a matter-loading platform comprising a substantially horizontal table supported on the machine structure above said recess and having upstanding walls along its edges, said table being provided with a matter-receiving opening disposed laterally with respect to said recess, an inclined chute leading from said opening into said recess for passing the matter from said table into said recess, and a magnet provided adjacent the matter-receiving opening underneath said table for arresting pieces of ferrous metals.

5. In an apparatus of the character described, a structure provided with a vertically extending matter-receiving recess having a rotor operatively arranged therein for cutting the matter received in said recess, a matter-loading platform comprising a substantially horizontal table supported on the machine structure above said recess to cover said recess fully and to overhang for substantial distances around all sides thereof, said table being of rec-

tangular shape and having upstanding walls at least along its three sides with a matter-receiving opening being provided in said table at one of the corners formed by said walls with said opening being disposed laterally with respect to said recess, an inclined chute leading from said opening into said recess and having its discharge opening on one side of the rotor in the direction of rotation of the rotor, and an apron provided in said chute and hinged at its top.
